FLOOR RACK FOR REFRIGERATOR CARS

Victor E. West, Chicago, Ill., assignor to Standard Railway Equipment Manufacturing Company, Chicago, Ill., a corporation of Delaware

Application January 24, 1938, Serial No. 186,509

5. Claims. (Cl. 105—375)

The invention relates to insulated refrigerator cars used to transport perishable commodities, such as vegetables, fruits, berries, meats, eggs, frozen fish, etc., and to maintain such commodities while in transit within a predetermined range of temperature, thus necessitating the use of a cooling means in the summer and a heating means in the winter. It has been found that perishable commodities which have not been allowed to get too cold (freeze) or too hot (bake) have a high market value because they have a longer storage life.

The invention specifically relates to a floor rack or means to support a lading in spaced relation to the usual insulated floor of the car to provide an air circulating flue below the lading.

The object of the invention is to provide a floor rack for a refrigerator car which is very strong to support vertical loads and has great strength in a horizontal direction (to resist the tendency of a shifting load to move the floor rack sideways) without materially retarding the flow of air below the floor rack or materially reducing the amount of air flow through the floor rack.

In the drawings:

Figs. 1 and 2 are longitudinal and lateral cross sections, respectively, of a railway refrigerator car having a bulkhead separating a refrigerant chamber from the lading compartment and a floor rack in the lading compartment. The arrows indicate the direction of movement of the air caused by its contact with the refrigerant and lading.

Fig. 3 shows a plan view of my improved floor rack.

Fig. 4 is a section on line 4—4 of Fig. 3.

Fig. 5 is a section on line 5—5 of Fig. 3.

Fig. 6 is a perspective view of one of the pedestals.

Fig. 7 shows a modified construction of my floor rack.

In the form of my invention illustrated the refrigerator car is provided with a bulkhead 2 separating the refrigerant chamber 3 from the lading compartment 4. The bulkhead 2 is provided with an aperture 5 adjacent the floor 6 of the car and an aperture 7 adjacent the ceiling 8 of the car with a solid wall 9 therebetween.

A refrigerant is supported by the grates 12 in the refrigerant chamber 3 in spaced relation to the floor 6 of the car and the basket (or netting) 13 spaces the refrigerant from the end wall 14 and bulkhead 2 to provide the flues 16—17. The apertured floor rack 18 supports the lading so as to provide the space or flue 20 which communicates with the flues 16—17. A refrigerant, such

as ice, in the refrigerant chamber induces a convection circulation of air from the flues 16—17 through the flue space 20 and the aperture 21 in the floor rack 18, and as the air is warmed by the lading, it rises and passes through the bulkhead upper opening 7, and thence through the flues 16—17, and being cooled by the refrigerant, repeats the convection cycle.

My improved floor rack comprises a plurality of panels 22 wherein each panel comprises a body 10 portion 24 provided with perforations 21 and formed with a marginal depending flange 26. The flanges of adjacent panels are secured preferably by welding (27) to form a substantially unitary floor rack.

The adjacent portions of adjacent flanges 26 are formed to provide hollow pedestals 28 which rest upon the floor 6 of the car. The side walls of the pedestals are provided with apertures 30 to allow air to move therethrough to the lading 20 compartment 4 of the car. The flange portions of the adjacent panels are preferably welded together (32) to form an integral panel. Drain holes 34 may be provided.

Fig. 7 shows a modification wherein the pedestals 28 on one side of each panel 36 are staggered relative to the pedestals on the opposite side of the same panel. The aperture 21 in the panels may be provided with flanges 38 to stiffen the body portions of the panels.

The panels are preferably provided with downwardly projecting corrugations or grooves 40 which extend substantially between certain pedestals 28 to stiffen the body portions of the panels therebetween. These grooves 40 preferably merge into the hollows of the hollow pedestals to form gutters to drain water from the upper surfaces of the panels.

The accompanying drawings illustrate the preferred form of the invention, though it is to be understood that the invention is not limited to the exact details of construction shown and described, as it is obvious that various modifications thereof, within the scope of the claims, will occur to persons skilled in the art:

I claim:

1. In a refrigerator car having a floor, a rack for supporting a lading in spaced relation to the floor to provide a flue therebetween, and means to induce an air current in said flue, said rack comprising a plurality of panels, each panel comprising a perforated body portion formed with a depending flange with the flanges of adjacent panels secured together and with the

adjacent portions of adjacent flanges formed to provide hollow pedestals resting upon said floor.

2. In a refrigerator car having a floor, a rack for supporting a lading in spaced relation to the

5 floor to provide a flue therebetween, and means to induce an air current in said flue, said rack comprising a plurality of panels, each panel comprising a perforated body portion formed with a depending flange with the flanges of adjacent panels secured together and with the adjacent portions of adjacent flanges formed to provide hollow pedestals resting upon said floor, 10 the pedestals on one side of each panel being staggered relative to the pedestals on the opposite side of the same panel.

3. In a refrigerator car having a floor, a rack for supporting a lading in spaced relation to the

15 floor to provide a flue therebetween, and means to induce an air current in said flue, said rack comprising a plurality of panels, each panel comprising a perforated body portion formed with a depending flange with the flanges of adjacent panels secured together and with the adjacent portions of adjacent flanges formed to

20 provide hollow pedestals resting upon said floor, said panels being provided with stiffening corrugations extending between the pedestals.

25

4. In a refrigerator car having a floor, a rack for supporting a lading in spaced relation to the floor to provide a flue therebetween, and means to induce an air current in said flue, said rack comprising a plurality of panels, each panel 5 comprising a perforated body portion formed with a depending flange with the flanges of adjacent panels secured together and with the adjacent portions of adjacent flanges formed to provide hollow pedestals resting upon said floor, 10 said panels being provided with stiffening corrugations extending between and merging into the hollow portion of the pedestals.

5. In a refrigerator car having a floor, a rack for supporting a lading in spaced relation to the 15 floor to provide a flue therebetween, and means to induce an air current in said flue, said rack comprising a plurality of panels, each panel comprising a perforated body portion formed with a depending flange with the flanges of 20 adjacent panels secured together and with the adjacent portions of adjacent flanges formed to provide hollow pedestals resting upon said floor, the side walls of said pedestals being provided with apertures.

VICTOR E. WEST.
